UNITED STATES PATENT OFFICE.

ALBERT JEFFERY'S, OF PHILADELPHIA, PENNSYLVANIA.

SHOE-MAKER'S JACK.

SPECIFICATION forming part of Letters Patent No. 350,137, dated October 5, 1886.

Application filed February 12, 1886. Serial No. 191,731. (No model.)

To all whom it may concern:

Be it known that I, ALBERT JEFFERY'S, a subject of the Queen of Great Britain, residing at Philadelphia, in the county of Philadelphia and State of Pennsylvania, have invented certain new and useful Improvements 5 in Shoe-Makers' Jacks, of which the following is a specification, reference being had therein to the accompanying drawings.

10 The object of my invention is to provide a shoe-maker's jack which will be simple and inexpensive in construction, and which may be adjusted in any desired position, so that the operator may conveniently perform the operations of lasting, stitching, pegging, heelng, trimming, burnishing, finishing, &c.

In the drawings, Figure 1 is a side elevation 20 of my jack, the dotted lines showing its position when partly raised; Fig. 2, a plan of the same; Fig. 3, a plan of the base of the jack; Fig. 4, a sectional elevation of the jack on line *x x*; Fig. 5, a side elevation of the jack in position for stitching; and Fig. 6, a plan of part of last-plate, showing lever for locking or 25 unlocking plate and bolt for securing lever.

A, Figs. 1, 3, 4, and 5, is a circular base having in it a radial slot, *a*, Fig. 3. This base is firmly secured by screws or bolts to a permanent table or stand.

30 B is a plate or disk which is placed upon the top of base A, and which carries the heel and toe seats C D for the last, as hereinafter described.

G is a journal-bearing furnished with an 35 arm, G', which passes through and is pivoted in the radial slot *a* in base A at *b*.

e is a journal-bearing on the plate or disk B, which is furnished with a vertical slot, O, Fig. 4, through which a pin, N, on heel-seat 40 may pass.

H is the journal, which is furnished with a spiral groove, I; J, a square bar passing through a corresponding hole in journal H. K K' are crown or bevel wheels carried upon 45 the ends of bar J.

L L' are corresponding wheels carried upon the journal-bearings e G.

c, Figs. 2, 4, and 6, is an opening in the plate or disk B, which has grooves E on its sides for 50 holding the toe-seat D, and d is an opening for holding the heel-seat C.

S, Fig. 3, is a clamp for clamping the plate B in any desired position. This clamp is pivoted in the base A at *k*, and is operated by a screw, S', which passes through the side of 55 base A.

The heel-seat C is constructed as shown in Fig. 4. Its front end carries a pin, N, which passes into the groove I in journal H. Its rear end is rounded off, so as to touch the plate B 60 in only one place, and its top carries a pin, F, which passes into a corresponding hole in the heel of the last.

The operation of the jack is as follows: The plate or disk B, which carries the toe and heel 65 seats D and C, is pivoted at its center upon the journal H, and this disk may be swung around H as a center to any desired position. As shown in the drawings, the wheels K and L are meshed one into the other, and the plate 70 B and journal H are consequently locked together, and if the plate B is turned the journal H turns with it. If the rod J is raised, throwing wheels K and L out of gear and wheels K' 75 L' into gear, the journal H will be locked to the journal-bearing G, and the plate B will turn, while the journal H will remain immovable. When the last is placed upon the seats 80 D and C, the pin F upon the latter passing into a hole in the heel of the last, and the pin N passing through a slot, O, in the journal-bearing e and into the spiral groove I in journal H, the bar J is raised, throwing wheels K and L out of gear and wheels K' L' into gear. The plate B is now turned around its center, 85 and the pin N travels down in slot I, drawing down the front end of heel-seat C, and throws the upper end toward the toe-seat D, firmly pressing the last against this seat and locking it so that it cannot be removed. The bar J 90 may now be thrown down, throwing wheels K and L into gear and wheels K' L' out of gear, and the plate B and the last may be swung into any desired position without unlocking the last. If the bar J is so placed that both pairs 95 of wheels K L K' L' are in gear at the same time, the whole jack is locked and cannot be turned in any direction. As before mentioned, the heel-seat C has its rear end rounded off and touches the plate B in one point only. This 100 allows the heel-seat to be tilted by the pin N being drawn up or down by groove I in jour-

nal H. It should also be mentioned that, in order to prevent jamming, the bottom of the heel-seat is not a straight line, but a curve, as shown in Fig. 4, and hence the heel-seat has but two lines of bearing, one on its rear end and one on its bottom. In order to raise and lower the bar J conveniently, I have a lever, M, pivoted to the plate B at f. This lever is turned up, as shown, and its upper end, Q, is bifurcated, Fig. 5, and passes beneath a collar, P, which is on the upper part of wheel K. The outer end of the lever M is furnished with three holes, g g' g².

R, Figs. 4 and 6, is a bolt which passes through the side walls, i j, of the opening c in plate B, and which is furnished with a head, h.

T is a helical spring surrounding bolt R, one end bearing against the head h and the other against the wall i. The outside end of the head h is conical, as shown in Fig. 6, and is adapted to enter the holes g g' g² in the end of lever M.

When the wheels K L are meshing, the head h of bolt R is in the hole g. If the wheels K' L' are meshing, the head h is placed in hole g², and if both pairs of wheels are gearing the head is placed in hole g'.

When it is desired to tilt the last, the plate B is tilted, as shown in Fig. 1 by the dotted lines, turning upon the screw b as a center. When the plate has been tilted sufficiently, the screw S' is screwed in and the clamp S is pressed firmly against the arm G' of journal-bearing G, and holds this arm and the plate B, &c., firmly in place. If desired, the screw b may be removed and the plate B, &c., placed as shown in Fig. 5. This would be a very convenient position for performing the operation of stitching.

The jack may be adapted to lasts of differ-

ent lengths by simply moving the toe-seat D from one groove E to another.

Having thus described my invention, I claim and desire to secure by Letters Patent—

1. The combination, in a shoe-maker's jack, of the base A, plate B, with journal-bearing e and holes c and d, for receiving last-seats C and D, last-seats C and D, journal-bearing G, with arm G', screw b, journal H, with slot I, pin N on last-seat C, bar J, with wheels K K', and wheels L L', all arranged and operating substantially as and for the purposes set forth. 50

2. The combination, in a shoe-maker's jack, of the base A, with radial slot a, plate B, with journal-bearing e and holes c and d, for receiving last-seats C and D, last-seats C and D, the former with pins F and N, journal-bearing G, with arm G', screw b, journal H, with slot I, bar J, with wheels K K', wheels L L', screw S', and clamp S, all substantially as and for the purposes set forth. 55

3. The herein-described device for raising and lowering the bar J, and for throwing the wheels K L K' L' in or out of gear, consisting of the lever M, pivoted at f, having its top Q bifurcated and its outside end furnished with three holes, g g' g², and bolt R, with conical pointed head h and helical spring T, all substantially as set forth. 65

4. The herein-described device for retaining the plate B and journal-bearing arm G' at any angle, consisting of the clamp S, pivoted to base A at k, and operated by a screw, S', substantially as set forth. 70

In testimony whereof I affix my signature in presence of two witnesses.

ALBERT JEFFERYS.

Witnesses:

EDWARD F. PUGH,
O. O. STODDARD.
